UNITED STATES PATENT OFFICE.

BENJAMIN F. DENNIS, OF DOVER, NEW HAMPSHIRE, ASSIGNOR OF ONE-HALF
TO HERBERT D. CAVERLY, OF SAME PLACE.

BOOK-HOLDER.

SPECIFICATION forming part of Letters Patent No. 427,558, dated May 13, 1890.

Application filed March 13, 1889. Serial No. 303,095. (No model.)

To all whom it may concern:

Be it known that I, BENJAMIN F. DENNIS, of Dover, in the county of Strafford and State New Hampshire, have invented certain new and useful Improvements in Book-Holders; and I do hereby declare the following to be a full, clear, and exact description of the invention, such as will enable others skilled in the art to which it appertains to make and use the same.

My invention relates to an improvement in leaf-holders for books.

The object is to provide a light, cheap, and inexpensive article susceptible of easy and quick application and capable of furnishing the requisite pressure upon the leaves without injury to them or damage to the bindings.

With this end in view my invention consists in certain novel features of construction and combinations of parts, as will be herein-after fully described, and pointed out in the claims.

In the accompanying drawings, Figure 1 is a view in perspective of my preferred form of holder, the dotted lines representing a book to which the holder is applied; and Fig. 2 is a similar view of a modification.

A represents the frame-work of the holder. This is composed of a single wire bent in any shape desired to serve as a gripping-surface, but preferably bent in the following manner: Starting at a central point 1, where a slight bend is made, it extends laterally in opposite directions for a short distance, when the wire is turned forward at nearly right angles at points 2 2, and from this point the ends of the wire are bent around about one and two-thirds time to form a pair of spirals 3 3, which leaves the wire at the rear of the spirals at points about opposite their centers. From here the ends of the wire are curved upward and backward and the bearing-loops 4 4 are formed in them, after which the extreme ends of the wire are bent outward to serve as stops 5 5, to be referred to hereinafter.

A second wire B, constituting another portion of the holder, is by preference bent in the following manner: At its middle an eyelet 6 is made by a complete spiral turn in the wire. From this point the wire extends rearward in the general shape of a letter V to

form a handle, and thence outward through the loops 4 4, in which the wire rocks. A sharp bend forward is made in the wire B just outside of these loops to form the spring-jaws 7 7, which afterward bend downward, and are rounded at the ends, so as not to scratch, mar, or tear the leaves. When the parts are assembled and the spring-jaws are depressed or in their normal position, the eyelet 6 is over the point 1, and, owing to the action of the spirals 3 3, the loops 4 4 always extend outward against the spring-jaws 7 7, so that when the jaws are thrown back they are always held by the stops 5 5. The jaws 7 7 are normally held in one of two extreme adjustments by the spiral spring 10, which extends from the point 1 to the eyelet 6. By its tension it always tends to hold these parts as close as possible to each other, and when the eyelet 6 is thrown forward and the spring holding-jaws 7 7 are down upon the leaves or against the spirals 3 3 they are the nearest to each other, and when thrown back in the opposite direction they are held against the stops by the contractile action of the spring.

In the modification the principle of the device is precisely the same as the former construction, and in the main the two are similar; but in a few respects, which will now be pointed out, they differ slightly. In this the wire A is bent to form a rounded portion 1 between the spirals 3 3 to receive the back of a book, and back of the spirals the wire is bent around to form the spring-elbows 5 5, which the tension of the spirals has a tendency to throw outward. At its extreme ends the wire terminates in the bearing-loops 4 4. A second wire B, bent in the middle to form a handle 6, extends outward through the loops 4 4, and thence forward against the spring-elbows 5 5 to form spring holding-jaws 7 7. In this device a third wire C is mounted on wire B to hold the loops 4 4 in place.

In the construction shown in Fig. 1 the jaws 7 are yieldingly held in closed position by spring 10, while in Fig. 2 the jaws 7 are closed by the spring-elbows 5. These elbows incline upwardly and outwardly, and hence are in the path of movement of the spring-jaws 7 as the latter are turned up. As the jaws are turned up or back, the elbows 5 yield in ad-

vance of the jaws, and consequently at all times exert a yielding pressure, tending to close the jaws. Of course it is understood that the devices are placed on an open book 5 by raising the jaws 7 and placing the book between them and the spirals, so that one spring-jaw bears on each leaf.

It is evident that slight changes might be resorted to in the form and arrangement of 10 the several parts described without departing from the spirit and scope of my invention, and hence I do not wish to limit myself to the precise construction herein set forth; but,

Having fully described my invention, what I 15 claim as new, and desire to secure by Letters Patent, is—

1. The combination, with a frame having spring-arms carrying loops at their ends, of movable jaws mounted in said loops, substantially as set forth.

2. The combination, with a frame having spring-arms, the latter terminating in loops, of movable jaws having bearings in said loops, substantially as set forth.

25 3. In a leaf-holder for books, the combination, with a frame having spring-arms, the latter terminating in loops, of yielding jaws

having bearings in said loops and adapted when open to receive pressure from the frame, substantially as set forth.

4. In a leaf-holder for books, the combination, with a frame consisting of a single wire bent to form spiral corners, bearing-loops, and stops, of a separate wire bent to form a handle and spring holding-jaws, said wire supported in the loops, and a spiral spring connecting the frame and wire, whereby pressure is given to the jaws, substantially as set forth.

35 5. The combination, with a frame having upwardly-projecting members at its opposite ends, said upwardly-projecting members terminating in loops, of a holder or wire B, mounted in said loops and provided with forwardly-projecting jaws, and means for yieldingly forcing said jaws downwardly toward the frame, substantially as set forth.

40 In testimony whereof I have signed this specification in the presence of two subscribing witnesses.
